UNITED STATES PATENT OFFICE.

CHARLES ARTHUR JACKSON, OF RIDGEWOOD, NEW JERSEY.

IMPULSE TURBINE.

Application filed October 19, 1923. Serial No. 669,469.

This invention relates to hydraulic turbines of the impulse type and more particularly to an improved means for controlling the speed of the same.

Such means have in the past commonly included a device for shutting off the power from the impulse jet which device has been actuated in response to the movement of the turbine governor. As a sudden shutting off of the supply of water to the jet may result in a severe rise of pressure in the penstock supplying water to the apparatus, it has been customary to provide an auxiliary means for temporarily turning or deflecting the jet upon a load rejection from the wheel so that a portion of the stream will not impinge against the runner blades. Such an auxiliary means may be made to follow quite closely the movements of the governor and thus produce an immediate regulation. The shutting off of the water from the jet is designed to take place subsequently to the deflection of the water from the runner blades and may be effected at such a rate as not to produce shock.

One of the objects of my present invention is to provide novel and improved means for automatically regulating the supply of water to the jet at a rate having a predetermined maximum which will safely avoid excessive pressure rise.

Another object of the invention is to provide means for quickly bypassing the flow or deflecting the jet upon a sudden drop in the load.

A further object is to provide an automatic means of this character which shall be thoroughly reliable in operation, and one which while permitting the rates of opening and closing of the nozzle to be adjusted within wide limits shall insure that the rates shall remain constant for any one adjustment.

Numerous other objects and advantages of my invention will appear from the following description taken in connection with the accompanying drawings wherein—

Figs. 1 to 3 are diagrammatic views of a turbine controlling mechanism embodying my invention, and showing successive positions occupied by the mechanism in cutting off the flow of the water to the nozzle.

Fig. 3^a is a similar view showing the jet deflector in a different position.

Fig. 4 is a central section partly in elevation showing the actual construction of a part of the mechanism shown diagrammatically in Figs. 1 to 3.

Fig. 4^a is an enlarged view of a detail of Fig. 4.

Fig. 5 is a diagrammatic development of the cooperating edges of the pilot valve and port openings.

Fig. 6 is a sectional view showing an operating piston with balanced peripheral pressures.

Fig. 7 is a diagrammatic development of the surface of the piston shown in Fig. 6, and

Fig. 8 is a central section partly in elevation illustrating a modified form of control means.

Referring more particularly to Figs. 1 to 3, 10 represents in outline the runner of an impulse turbine, 11 a nozzle for directing the jet of water against the blades of the runner, and 12 a deflector mounted on the pivoted arm 13 and movable into the path of the jet 14 to deflect the same and thus cause a greater or less portion of the jet to be diverted from the runner blades. A plunger or needle 16 operates within the nozzle 11 to enlarge or restrict the opening through the nozzle so as to vary the diameter of the jet.

Upon a drop in load it is desirable to reduce the driving force on the wheel 10 immediately to avoid over speeding. To accomplish this the deflector 12 is moved into the jet an amount corresponding to the load reduction. The deflecting surface 60 has a slight curvature as shown so that when its lower edge 60' has reached the center line of the nozzle the entire jet will be deflected a sufficient amount to clear the water wheel buckets (see Fig. 3^a). The deflected jet 14 will not follow the direction of the deflecting surface 60 but will approximate a path which will be a bisector of the angle A between the jet axis and the deflecting surface. The deflecting surface 60 therefore moves into the jet from the side nearest the wheel 10 and is so directed that as it moves down it will divert the jet more and more until, if the edge 60' reaches the axis of the nozzle, the entire jet is turned clear of the buckets.

This deflection of the jet reduces the driving force on the wheel.

ing force quickly without danger of pressure rise in the supply line, but the deflected water is wasted and therefore this deflection or bypassing of the water is combined with a relatively slow movement of the nozzle needle 16 to reduce the size of the jet to correspond to the reduced load.

Upon increase in the load the deflector 12 moves away from the jet and the nozzle needle opens at a regulated rate which is adjusted to prevent an excessive drop in pressure in the supply line.

In the system as illustrated in the drawings the deflector and nozzle needle are controlled by a governor G of usual construction having a fluid pressure cylinder 19 within which is a piston connected to the lever 20 so that when the speed of the turbine is reduced below normal pressure will be admitted to one side of the piston to move the lever 20 counter clockwise and when the speed is above normal pressure will be admitted to the other side of the piston to move the lever 20 in a clockwise direction. The action of the governor on a drop in load, for instance, is to turn the lever clockwise according to the excess in speed above normal. This through deflector 12 and needle 16 reduces the speed to slightly below normal and this reduction in speed causes the governor to return the lever 20 slightly counter-clockwise to the exact position required by the new load. The lever 20 serves to reciprocate the rod 21 which is connected at one end with the pivoted arm 13 of the controlling deflector 12. A nozzle controlling lever 24 is pivoted at 25 and attached to the rod 21 by a lost motion connection which comprises springs 26 which press at their outer ends against collars 27 fixed on the rod 21, and at their inner ends against the end 28 of the lever 24. The lever 24 serves to actuate the pilot valve piston 30 which slides within a second or operating piston 31 operating in the cylinder 32. The second or operating piston 31 has secured to one end, the rod 34 which serves to operate the needle or plunger 16 used to control the supply of water to the jet 14. At its other end the piston 31 carries the rod or tube 40 having adjustable stops 41 and 42 arranged to engage the lever 24 and limit its pivotal movement and consequently limit the relative movement of the pilot valve 30 in the piston 31.

The cylinder 32 of piston 31 is provided with a fluid inlet passage 44 which is adapted to be supplied with oil under pressure from a pressure system (not shown). Communicating with the central bore 45 of the piston 31 is a passage 36 which leads to the space 37 within the cylinder 32 at the left of the piston 31; also a passage 38 which leads to the space 39 within the cylinder 32 at the right of the piston 31; a passage 46 com-

municating with the inlet passage 44 and passages 48 and 49 in communication with the outlet passage 50.

The pilot valve 30 is formed with annular spaces 54, 55 formed between the valve heads 56, 57 and 58. In the position shown in Fig. 1 the head 57 closes the inlet passage 46 while passages 36, 38, 48 and 49 are all open. With the parts in the position shown if a portion of the load on the turbine is suddenly rejected the speed of the runner will increase with the result that the governor will move the rod 21 to the right thus causing the deflector 12 to tilt to a position to deflect the jet 14 so that a portion of the jet passes by the runner and does not impinge against the blades. This motion of the rod 21 also causes a rotation of the controlling lever 24 in a counter-clockwise direction and a movement of the valve piston 30 to the left into the position shown in Fig. 2. This as will be seen opens communication between the inlet and the space 39 at the right of the cylinder 32 and the oil being forced into this space moves the piston 31 and with it the needle 16 to the left so as to restrict the flow of water through the nozzle 11. The piston 31 continues to move until the parts finally reach the position shown in Fig. 3 as will be more fully described as follows.

It will be noted that by reason of the engagement of the lever 24 with the stop 41, which will occur when the lever has been turned through a certain angle, the end 28 of the lever 24 will be prevented, for the time being from following the rod 21 to the full extent of its stroke. Any motion of the rod 21 in excess of this distance will result in a compression of the spring 26 at the left of the lever 24, the spring to the right being held by a central stop 115 secured to the rod 21 and movable therewith, and a collar 114 movable on rod 21. As shown in Fig. 4 and later described, the lever 24, like the lever 95, is adapted to pass over the central stop 115 and engage the collar 114. As the operating piston 31 begins to move under the pressure of the oil at one end of the piston the stop 41 is likewise moved in such a direction as to permit the lever 24 to continue its counter-clockwise rotation. The time lag between the relatively quick motion of the deflector 12 and the slow movement of the needle 16 will depend upon the rate at which oil is forced into the cylinder 32 and this in turn will depend upon adjustment of the stop 41 which controls the extent to which the passage 46 is uncovered by the motion of the piston 30. By proper adjustment of stop 41 the widest opening of port 46 will be so regulated that the oil can pass at a rate having a predetermined safe maximum and the piston 31 and needle 16 will be moved to restrict the opening through the 120 125 130 135

nozzle 11 slowly, that is, at such a rate that there will be no danger of damage due to water hammer or sudden surges in the pipe line.

The result of the motion of the deflector 12 toward the position shown in Fig. 2 will be to deflect more and more of the water away from the runner buckets and consequently lessen the driving torque. The runner will therefore slow down and the governor will act to stop further motion of the lever 13 and slightly reverse it. The motion of the piston 31 will have continued until the parts assume the position shown in Fig. 3 in which the inlet passage 46 is again closed by the valve head 57. Upon a load rejection the governor first moves the deflector 12 a sufficient distance to bring the turbine speed back to normal. Then as the needle 16 is gradually closed by the automatic device indicated generally at 18 the deflector 12 is slowly moved away from the jet by the governor until the diameter of the jet has been reduced sufficiently to drive the turbine at normal speed, the deflector in the meantime having reached its normal position which is just clear of the top of the reduced jet. This will be the new position of rest until some further change in the load occurs. For each adjusted position of the needle, therefore, and with the lever 24 in central position between stops 41, 42 (Figs. 1 and 3) there will be a correspondingly sized jet and the linkages are such that the position of the edge 60' of the deflector will be just clear of the jet whatever its size.

The motion of the plunger 16 will cause the jet to decrease in diameter so that it will occupy a space just below the edge 60' of the deflector 12 in its new position. The deflector will therefore be in a position ready to enter the jet immediately upon any further rejection of the load.

In case of an increase in load the speed of the runner will decrease and the rod 21 be moved by the governor 19 toward the left. This will raise the deflector 12 but as the same is normally free from the jet this action in itself will not effect any regulation. Motion of the rod 21 however will operate to rotate the lever 24 in a clockwise direction and thus move the valve piston 30 and uncover the passage 46 and permit fluid to flow to the left of the piston 31. The stop 42 may be adjusted to permit the valve head 57 of the piston 30 to open the passage 46 to any predetermined maximum according to the highest safe rate of opening of the needle 16. This rate of opening will usually be greater than the rate of closing and the result is that oil will enter the cylinder 32 at a more rapid rate and move the plunger 16 more rapidly to enlarge the opening of the nozzle 11. The piston 31 will continue to move toward the right until the valve pis-

ton 30 again centers itself with the passage 46 closed and the end 28 of the lever 24 midway between the collars 27.

It is of course possible to construct the deflector so that in its normal position of rest it will serve to deflect a portion of the jet 14. Under such circumstances a movement of the governor lever 20 in a counter-clockwise direction and the consequent raising of the deflecting ring 12 (which action would take place under increased load) would cause more of the water of the jet 14 to impinge against the blades and thus act quickly to apply a greater torque to the runner. In the preferred construction however the deflecting face 60 of the ring 12 is normally just free of the jet 14 and there is therefore no continuous waste of water as would be the case were the deflector always in the stream.

The controlling mechanism as above described is adapted for manufacture as a self contained unit which may be applied to needle nozzles of existing turbines.

Referring more particularly to Fig. 4 which shows one form of operating means for the plunger, 70 indicates a cylindrical casing having heads 71 and 72 each formed with a stuffing box 73 for the piston rod 74. This rod serves to actuate the needle which controls the opening through the nozzle in the manner well-known in the art.

The casing 70 is provided with tapped openings 75 and 76 connected respectively with a supply and exhaust conduit 77 and 78. Secured to the rod 74 is the piston head 80 which is formed at its outer surface with depressions 81 and 82 communicating respectively with the inlet and outlet passages. The depression 81 which is on the lower side of the piston head 80 covers a somewhat greater peripheral area than the depression 82. The force of the oil acting upon the top wall of this depression assists in sustaining the weight of the piston head 80 and connected parts. The rod 74 is formed with a central bore 84 and the rod and piston head 80 are provided with the exhaust passages 86 and 87 which connect with the depression 82; also an inlet passage 88 which communicates with the depression 81; the passage 89 which connects the bore 84 with a space at the right of the piston head 80 and a passage 90 which connects the bore 84 with the space at the left of the piston head 80. Adapted to move inside the bore 84 is a valve piston 92 formed with annular depressions 93 and 94 positioned as shown in the drawing. This plunger receives its motion from the lever 95 through a connecting link 96 which is pivoted at one end to the end of the valve piston 92. As shown in Fig. 4^a lever 95 receives its movement from rod 121. The springs 126 on the rod press against washers 113, 114 which

have a definite fixed central position determined by a collar 115 rigidly fixed to rod 121. Therefore when spring 126 at the right or left of lever 95 is compressed the 5 spring at the left or right will remain in its central position and will not follow up the movement of end 128 of the lever which is pivotally connected to the sliding collar 116.

The piston 92 adjacent to its point of adjustment to the link 96 is screw-threaded to 10 receive nuts 98 and 99 engaging these threads. The piston rod 74 is formed with an enlarged portion provided with openings 100 and 101 within which the nuts 98 and 15 99 move an intervening web 102 between the openings 101 and 102 serving as an abutment to stop the motion of one of the other of the nuts. The nuts and web 102 thus 20 serve as adjustable stops for limiting the motion of the piston rod 92 relative to the piston head 80 and therefore determine the extent of the opening of passages 89 or 90 and the speed of the plunger in controlling the size of the jet. Beyond the enlarged 25 portion of the rod 74 the same is formed with a screw threaded portion 103 adapted to be engaged by a hand wheel 104. The hub 105 of the hand wheel is formed with an extension 106 having an external annular 30 slot 107. This slot is adapted to receive a key 108 which is slidable in slots 109 formed in a cap 110 extending rearwardly from the cylinder head 72. Insertion of the key 108 serves to prevent longitudinal movement of 35 the hand wheel relative to the fixed structure when the same is rotated and thus enables the rod 74 to be moved. When the automatic operation is desired rather than a hand operation the key 108 is removed and 40 the hand wheel is turned to the outer end of the rod 74.

The piston head 80 is formed with a bore 111 adapted to receive a pin 112 projecting inwardly from the head 71 of the casing 70 45 and so prevents rotation of the piston head within the cylindrical casing.

The ports where the pressure and exhaust connections open into the central pilot valve chamber may be of any desired shape to give 50 a preferred shape and rate of opening as the pilot valve moves along the port edge. These ports may, for instance, be elongated or V-shaped as shown in Fig. 5.

Instead of having the pressure supply on 55 one side of the piston 32 and the exhaust on the other as shown in Figures 1 to 4, the pressure and exhaust areas may be balanced on opposite sides as shown, for instance, in Figs. 6 and 7. The pressure chambers 181 and 181' are arranged below and 60 above the cylinder and the exhaust chambers 182 and 182' on opposite sides; the pressure chambers being connected by the groove g and the exhaust chambers by the groove 65 g'. The relative sizes of chambers 181 and

181' may be arranged to overbalance upward and just support the weight of the piston, so that it will slide freely without any tendency to become set in a fixed position. 70

In the construction above described it will be impossible for the plunger or needle 16 to be moved suddenly to close the nozzle for the reason that time must elapse to enable the liquid to pass out of the casing 70 to 75 permit the motion of the piston head 80 and actuating rod 74. This construction also reduces to a minimum the possibility of the valves operating improperly because of being clogged with sediment from the oil, 80 since each time the pilot valve opens and closes it automatically cleans itself of all foreign matter such as may be due to leakage while the valve is closed and which has accumulated around the valve clearance. 85 The rate of movement of the needle 16 both in opening and closing may be different from the rate of movement of the governor and of the deflector, for instance, with a deflector movement of one second the 90 needle movement may be twelve seconds in closing or the opening movement of the needle for a corresponding increase in the load may be ten seconds. Thus the rates of movement of the needle in opening and in 95 closing are not only different from each other but are also different from the governor rate and deflector.

In the modification shown in Fig. 8 the nozzle 11' has its needle 16' with stem 34' and piston 31' pressed to the left toward closing by the spring s the pressure of which is adjusted by the sleeve 140. Fluid pressure to open the needle 16' is supplied through pipe 77' and is controlled by pilot valve 30'. The control rod 21 through springs 26 and connection 28' tips lever 24' pivoted at 25' and connected to the pilot valve 30' through links 96' and collar 140', adjustable stops 98', 99' being provided to limit the movement of the pilot valve with relation to the piston 31'. Movement of rod 21 toward the left moves pilot valve 30' to the right to uncover port 141 and admit pressure from chamber 142 to port 143 leading to the end chamber 144 of cylinder 145. Fluid pressure in chamber 144 moves the piston 31' to the right compressing spring s and enlarging the opening through nozzle 16'. The movement of the piston 31' to the right closes the port 141 and shuts off the pressure. 110

To close the needle 16' the rod 21 moves toward the right and slides the pilot valve 30' toward the left to open port 146 thus connecting chamber 144 to the exhaust chamber 147, and outlet 78' and permit the spring s to expand and move the piston 31', stem 34' and needle 16' to the left toward 125 closed position. 130

Instead of the fluid pressure control the hand wheel 150 having its hub 151 threaded on the stem 34' may be used to move the needle 16' open against the tension of 5 spring s. During operation of the fluid pressure means the hand wheel is backed off away from the thrust bearing 152 supported on the packing gland collar 153.

This single acting cylinder control is 10 advantageous in that it will automatically close the nozzle needle 16' in case the oil pressure or the fluid pressure control means fails. Instead of the spring s a constant closing pressure may be applied, for instance, by making the needle bulb 16' large 15 and the stem 34' small, thereby causing a constant tendency of the pressure in the nozzle to close the needle; or pressure may be introduced into the end chamber 154 of 20 the cylinder 145.

The various parts of the apparatus shown may be made adjustable wherever desired so as to permit a final adjustment of the parts when installed. This adjustment may 25 be changed if required, for instance, by a change in the operating head on the nozzle or other conditions determining the preferred action of the governor. For instance the length of the rod 21 may be made adjustable or the relative lengths of the ends 30 of the lever 24 so as to vary the relation between the needle setting and the deflector setting.

Instead of a deflector it is obvious that 35 other means may be used to reduce the pressure as the needle closes and the invention is not confined to the specific embodiments shown and described but is intended to cover such modifications thereof as fall within the 40 scope of the appended claims.

I claim:

1. Governing apparatus for a hydraulic turbine comprising means for regulating the flow to the turbine runner and means for diverting said flow, both of said means being 45 governor controlled, and connections between said regulating means and the governor comprising a lost motion connection permitting a predetermined invariable rate 50 of opening and closing movement of the regulating means irrespective of the rate of change of load, and adjustable means for limiting said regulating means to a predetermined maximum rate of opening and closing 55 movement.

2. Governing apparatus for an impulse turbine comprising a needle regulating the size of the jet, and a deflector having a surface moving into the jet from the wheel side 60 thereof and formed to deflect the whole of the jet away from the wheel when and only when the entering edge of the deflector reaches the center of the jet.

3. Governing apparatus for an impulse 65 turbine comprising a needle regulating the

size of the jet, and a deflector having a surface moving into the jet from the wheel side thereof and formed to deflect the whole of the jet away from the wheel when and only when the entering edge of the deflector 70 reaches the center of the jet and means for interconnecting said needle and deflector so that the edge of the deflector is just clear of the jet surface at each adjusted position of the needle.

4. Governing apparatus for an impulse turbine comprising a needle for regulating the size of the jet, and a deflector having a surface moving into the jet from the wheel side thereof, said surface being so formed that when the jet is entirely deflected from the wheel, the axis of the deflected jet will approximately bisect an angle, the sides of which are formed by the normal jet axis, and the line along which said deflector surface would follow when extended.

5. Governing apparatus for an impulse turbine comprising a needle for regulating the size of the jet, and a deflector having a surface moving into the jet from the wheel side thereof, said surface being so formed that when the jet is entirely deflected from the wheel, the axis of the deflected jet will approximately bisect an angle, the sides of which are formed by the normal jet axis and the line along which said deflector surface would follow when extended, the entering edge of said deflector being at the normal jet axis only when complete jet deflection is obtained.

6. In a turbine adapted to receive water from a source of supply, means for controlling said turbine by varying the supply of water from said source, means for diverting water from the turbine runner, a governor, a connection between said governor and said latter means whereby said latter means responds without substantial delay to the action of said governor, a fluid operated device comprising a piston adapted to actuate said supply controlling means, a valve member operated in response to said governor and movable relative to said piston to admit fluid pressure to one side of said piston and to relieve pressure from the other side, whereby said supply controlling means is moved in response to said governor and adjusting means limiting the relative movement between said valve member and piston to vary the rate of movement of said supply 110 controlling means.

7. In a turbine adapted to receive water from a source of supply, means for controlling said turbine by varying the supply of water from said source, a second means for controlling said turbine, a governor, a connection between said governor and said second means whereby said second means responds without substantial delay to the action of said governor and a fluid operated 125

- device adapted to actuate said supply controlling means, said device comprising a cylinder, a piston movable therein and formed with a bore and inlet and outlet passages communicating with said bore, a piston valve movable within said bore, means cooperating with said valve and movable with said piston for controlling the relative movement between said piston and valve, operating means for said valve and a connection between said valve and governor and a resilient lost motion connection between said valve and governor.
8. In a turbine of the impulse type a runner nozzle adapted to form a jet of water, means for controlling said turbine by varying the quantity of water supplied to said jet, means for changing the direction of the water of said jet so that a portion only of said water is effective to operate said runner, a governor, a connection between said governor and said latter means whereby said latter means responds without substantial delay to the action of said governor, a member connected directly to said governor, a controlling means for said first-named means comprising a connection biased to a certain position relative to said member, means for limiting the extent to which said connection may follow the movements of said governor in either direction whereby the rate at which said first named means is operated is limited and means responsive to the condition of said first named means for varying the limiting effect of said last named means.
9. Regulating means for the jet of an impulse turbine comprising a nozzle, a needle, and a fluid pressure operated piston connected thereto to move said needle, a pilot valve for controlling the fluid pressure supply to said piston; said valve being normally movable during piston movement, and adjustable means for limiting the movement of said pilot valve to restrict the rate of movement of the piston to a predetermined maximum.
10. Regulating means for the jet of an impulse turbine comprising a nozzle, a needle, and a fluid pressure operated piston connected thereto to move said needle, a pilot valve normally movable during needle movement for controlling the fluid pressure supply to said piston, and adjustable means for limiting the movement of said pilot valve to restrict the rate of closing movement of the piston to a predetermined maximum.
11. Regulating means for the jet of an impulse turbine comprising a nozzle, a needle, and a fluid pressure operated piston connected thereto to move said needle, a pilot valve for controlling the fluid pressure supply to said piston, normally movable during needle movement and adjustable means for limiting the movement of said pilot valve to restrict the rate of closing movement of the piston to a predetermined maximum and separately adjustable means for limiting the movement of said pilot valve to restrict the rate of opening movement of the piston to a predetermined maximum.
12. In an impulse turbine a nozzle, a needle for regulating the size of the jet from said nozzle and means for moving the needle comprising a cylinder and a piston movable therein, means to supply fluid to said cylinder, the sides of said piston and cylinder having between them an inlet chamber so constructed and arranged that the pressure of the fluid therein assists in sustaining the weight of the piston.
13. In an impulse turbine a nozzle, a needle for regulating the size of the jet from said nozzle and means for moving the needle comprising a cylinder and a piston movable therein, means to supply fluid to said cylinder, the sides of said piston and cylinder having between them opposite connected inlet chambers so arranged that the inlet pressure assists in sustaining the weight of the piston.
14. In an impulse turbine a nozzle, a needle for regulating the size of the jet from said nozzle and means for moving the needle comprising a cylinder and a piston movable therein, means to supply fluid to said cylinder, the sides of said piston and cylinder having between them opposite connected inlet chambers and opposite connected discharge chambers so arranged that the inlet pressure assists in sustaining the weight of the piston.
15. Governing apparatus for a hydraulic turbine comprising means for regulating flow to the turbine runner and means for diverting said flow, governor mechanism, and connections between said regulating and diverting means and governor mechanism including a lost motion connection operative during opening movement of said regulating means, whereby a time delay is had between the operation of said regulating means and diverting means.
16. Regulating means for a turbine flow control mechanism including a fluid pressure operated piston connected to said controlling mechanism to move the same, and a pilot valve normally movable during said movement to control the supplying of fluid which operates said piston.
17. Regulating means for the flow control mechanism of a turbine, comprising a fluid pressure operated piston connected to said controlling mechanism to move the same, means whereby said piston is moved in an opening direction by fluid pressure, and means for directly controlling the supplying of operating fluid to said piston, said latter means including a pilot valve normally movable during piston operation.
